UNITED STATES PATENT OFFICE.

WOODFORD SHANNON, OF LOUISVILLE, KENTUCKY.

SPRING STRUCTURE.

1,313,341.

Specification of Letters Patent.

Patented Aug. 19, 1919.

Original application filed December 14, 1915, Serial No. 66,688. Divided and this application filed August 21, 1917. Serial No. 187,486.

To all whom it may concern:

Be it known that I, WOODFORD SHANNON, a citizen of the United States, residing at Louisville, in the county of Jefferson and State of Kentucky, have invented certain new and useful Improvements in Spring Structures, of which the following is a specification.

This invention is a division of an application

10 filed by me on or about December 14, 1915, Serial No. 66,688 and relates to spring structures particularly adapted for seats and the like of the type in which longitudinal supports or side rails with transverse supports or slats, extending between them and spaced by intermediate longitudinal members or braces, are combined to make a frame upon which is mounted an area of vertically disposed coiled springs 15 secured to the slats of the frame by their lower coils and tied together at or near their upper coils by binding elements which space the springs apart. The invention has for its objects to improve the construction 20 of such a spring structure in each of its main parts, to wit, the longitudinal supporting members or side rails of the frame; the connections between the bracing members and the slats; the mounting of the springs upon 25 the slats; and the binding elements for spacing the upper portions of the springs apart.

Accordingly, one feature of the invention consists in mounting the side rails of the frame for shifting from one supporting 30 position to another, as by swinging bodily through an angle of, say 90°, and having the side rails formed to receive one type of bed rail, for example, that of an iron bedstead, corresponding thereto in distance apart, 35 when the rails of the frame are in one position, and adapted to receive another type of bed rail, similarly, for instance, the rails of a wooden bedstead having a slat ledge, when the rails of the frame are in their other 40 position; and another feature, subordinate to the foregoing, consists in uniting the transverse members of the spring frame to said longitudinal rails, by means of hinging 45 connections, preferably comprising ears connected through pintles with the slats, and through integral riveting ends with the side rails of the frame.

Another feature consists in mounting the bracing members on the slats, through means of deflected or downwardly offset 5 crimps shaped to receive and conform to three faces of the slat, and having tongues struck up from the braces in position to be pressed down upon the fourth face of the slat to hold the crimp in embracing relation thereto.

Another feature consists in mounting each spring with its lower coil resting upon a slat and encircling the crimp adjacent thereto, and holding the spring in such relation 65 by other tongues struck up from the brace, on either side of the crimp, and embracing the lower coil at opposite ends of a diameter which is at right angles to that by which the coil seats upon the slat; these coil-embracing tongues, incidentally, enabling the coil to resist spreading of the crimp which would release the slat.

Another feature consists in tying the upper ends of the springs together in pairs, 70 through means of substantially U-shaped binding elements which space the springs in one direction by the parallel sides of the binders, and in the other direction by their closed ends. And a feature subordinate 75 thereto consists in interlocking the closed end of each binding element with adjacent points on a pair of springs, by introducing the free ends of the next ensuing binder, beneath crimps in the binder and over the coil 80 of the spring, this introduction taking place while the binder is perpendicular to the spring area, and the introduced ends being provided with deflected portions which engage the intersected parts when the binder 85 is turned down to the horizontal position with its own closed end in relation to the next pair of springs to receive the next 90 interlocking ends of a binder.

The invention will be fully understood 95 upon reference to the detailed description of an illustrative embodiment of its several features as disclosed in the accompanying drawing. In said drawing:

Figure 1 is a plan view of a bed spring 100 with intermediate portions cut out both longitudinally and transversely, but showing four springs in substantially the relation which they would assume in practice,

to other springs longitudinally and transversely spaced therefrom.

Fig. 2 is an end view of the same.

Fig. 3 is a detail view illustrating the assembly of a brace with the slats.

Fig. 4 is a similar view illustrating the assembly of the binding elements with the upper coils of the springs.

Fig. 5 illustrates the assembly of a hinging tab or ear with a side rail, and

Fig. 6 is a detail view of the hinging tab or ear separated.

1 represents the side rails, 2 the transverse supporting members or slats, and 3 the braces of the supporting frame. The side rails 1 are preferably made of structural metal L-shape in cross section and having riveted to them, as shown at 4, hinging tabs or ears 5 in position to support the slats 2. Slats 2 are connected with hinging members 5 through means of pintles 6, thereby adapting side rails 1 to assume the position shown in Fig. 1, or by full lines in Fig. 2, in which they are adapted to receive and rest upon the side rails of an iron bedstead or to assume the position shown in dotted lines in Fig. 2, when they will be adapted to rest upon and hold the spring surface at the upper elevation above the slat-supporting ledge of a wooden bedstead. The better to adapt the side rails to rest upon slat ledges of a wooden bedstead, when the said side rails are turned downward, said rails are provided with supporting feet 7 near their respective ends, which may be of any suitable construction, such for instance as sections of L-bar riveted to the rails as shown. To sustain the side rails in the dotted line position under the load imposed in the use of the structure, any suitable form of latch 8 may be employed. The form of latch illustrated is pivoted at 9, adapted to engage the side rail by its beak 10, and provided with flexible arm 11 adapted to catch beneath the slat.

Braces 3 are assembled with the slats 2 through means of downwardly offset crimps 12 conforming to the bottom and two vertical sides of the slat, and provided at top 50 with tongues 13 closed down over the top edge of the slat, as shown in Fig. 1. Braces 3 are corrugated or ribbed intermediately of their crimps to stiffen them and adapt them to serve as compression members or 55 struts between the slats, while to secure them in the direction of tension, and prevent opening their crimps, they are tied together by the lower coils of the springs 14 as will now be described.

60 In mounting the springs upon the frame, each spring bears with a diameter of its lower coil 14^b adjacent its down-turned end 14^c resting above a slat and with its intersecting diameter coinciding with spring-at-

taching tongues 15, the coil of the spring 65 encircling said tongue 15 as well as the crimp of the brace. Tongues 15 are then bent outwardly over the coil of the spring, and the spring is securely locked in position. In practice, the plane of the brace is sufficiently below the upper plane of the slat, 70 to leave the lower coil under flexing strain and thus hold the parts against vibration.

To position the upper ends of the springs, any suitable form of outer rim 16 known 75 to the art is employed to provide an outer margin and to the longitudinal sides of this rim 16, the adjacent springs are firmly bound by any known type of clip 17. Within the marginal rim, the springs are firmly tied 80 together in spaced relation by the novel form of tying element 18. This comprises a substantially U-shaped member having a closed end 19 adapted to lie on one side of (preferably beneath) the plane of the upper 85 coils 14^d of two adjacent springs near their opposed points and provided with crimps 20, shown more plainly in Fig. 4, by which they are adapted to intersect the plane of said coils; and said tying members are also 90 provided with free interlocking ends 21 extending transversely so as to adapt them to enter beneath the crimp 20 and over the top coils 14^b and then downwardly to engage 95 said top coil and prevent unlocking of said ends. The interlocking ends are readily introduced while the tying member stands perpendicularly to the spring surface as the down-turned ends are then in the plane of the top coils. After thus introducing the 100 ends, it is merely necessary to swing the tying member downward and introduce its closed end with previously formed crimps beneath the next pair of top coils when it will be ready to receive the interlocking ends 105 of the next tying member. This method of assembly is followed until the row of springs is completed. The end-tying members will, of course, be united to the transverse bars of the marginal rim 16 in substantially the 110 manner shown.

In addition to the described relations between the tying members and the springs which their closed ends unite in pairs, certain of the springs may have the free ends 115 of their top coils deflected as shown at 14^a and engaging the closed ends of the tying members in a direction to resist unwinding of the springs. This is desirable for those springs which are not in such position as to bring their said free ends within reach of the marginal rim member or other part adapted to resist unwinding.

I claim:—

1. In a spring structure, the combination 125 of a series of transverse slats, side rails, and ears rigidly connected to said side rails and pivotally connected to the ends of said slats

so that in either position of the side rails they act as support for the spring structure.

2. In a spring structure, the combination of a series of transverse slats, angle iron side rails, and ears rigidly connected to one flange of said angle iron side rails and pivotally connected to the ends of said slats,

so that in either position the other flanges or members of the angle iron side rails act as support for the spring structure. 10

The foregoing specification signed at Louisville, Kentucky, this first day of August, 1917.

WOODFORD SHANNON.
